UNITED STATES PATENT OFFICE.

HARRY O. SCHUESSLER, OF PERU, ILLINOIS.

APPARATUS FOR ELECTROPLATING.

1,299,624.

Specification of Letters Patent.

Patented Apr. 8, 1919.

Application filed January 28, 1918. Serial No. 214,096.

To all whom it may concern:

Be it known that I, HARRY O. SCHUESSLER, a citizen of the United States, residing at Peru, in the county of La Salle and State 5 of Illinois, have invented certain new and useful Improvements in Apparatus for Electroplating, of which the following is a specification.

This invention relates to electro-plating apparatus especially adapted for those processes in which the work is subjected to electrolysis in a series of different baths, such for example as when nickel plating, the work is generally exposed in a bath of 10 sulfate of copper, thence in a rinsing bath, and finally in a nickel plating bath. Heretofore, in the practice of such plating on a large scale the matter of handling the articles or pieces to be plated and transferring 15 them from one bath to another at the proper intervals entailed greater cost than should be necessary because of the lack of time and labor saving facilities for the purpose.

In the present invention, I have aimed, 20 primarily, to provide apparatus by means of which electro-plating of the character described may be performed more economically and expeditiously and with more uniform results than has been heretofore possible.

In furtherance of this general object I have contemplated the provision of novel means for mechanically handling and carrying the work to be plated from one bath to another of a series at timed intervals, so 25 that the successive plating and rinsing operations of whatsoever nature required are performed in proper sequence and timed relation. I have also provided novel means for automatically closing and opening the electric circuits of the respective baths, this being controlled by the act of placing the work into and removing it from the baths, so 30 that electric current is consumed only during the actual periods of electrolysis.

These and other objects and attendant advantages will be appreciated by those skilled in the art of electro-plating as the invention becomes better understood by reference to the following description when considered in connection with the accompanying drawings, in which—

Figure 1 is an elevation, partly in section, of one working example of an electro-plat-

ing apparatus embodying my improvements; and

Fig. 2, a vertical sectional view of the apparatus taken substantially on the line 2—2 of Fig. 1.

As mentioned above, my improvements 60 are applicable in general to various electro-plating processes, although in the following illustration I have taken simply as an example, a series of three baths such as are employed for nickel plating. In this particular case, the work is cleansed and coated with sulfate of copper in the first bath by electrolysis as is well understood; the second bath 4 is simply of water for rinsing purpose; and in the third bath 5 the work 70 is nickel plated by electrolysis. The baths 3 and 5 contain the requisite anodes 6 and 7 respectively, which are the positive electrodes and receive electric current from a suitable source, such as from a generator 8. 75 The negative electrodes designated generally by characters 9 and 11, normally out of circuit, are of novel construction as will be presently seen.

My improvements contemplate the provision of work holders designed to be carried successively to the several baths and, when the work has been immersed therein, to be brought into contact with the negative electrodes thereof, so that the circuit of the 80 bath is closed, the work becoming the cathode, and electrolysis ensuing. In other words, by moving the work holders into and out of electro-plating positions the circuits of the respective baths are automatically 85 closed and opened so that the electrolytic action takes place only during the periods that the work is immersed in or fully exposed to the solution. My improvements further contemplate, as will presently be seen, 90 the provision of an endless carrier for moving the work holders to and from the several baths at the proper intervals so that closing and opening of the circuits becomes 95 automatic.

The work holders in the present instance are each in the form of a rod 12 from which is adapted to be suspended one or more articles to be plated. As shown, these articles are in the form of plates 13 of sheet metal 105 attached to the holders through the agency of suitable hangers 14. The work holders are adapted to be supported immediately

above each bath by means of supporting members which constitute the negative electrodes. These electrodes or supporting members 9 and 11, mounted at each end of the baths 3 and 5 and insulated therefrom, are constructed to provide V-shaped supporting surfaces 15 adapted to receive and support the ends of the work holding rods 12. The rods as shown in Fig. 1, extend beyond the supporting members 9 so that they may be engaged at their extremities by carriers which will be presently described, and lifted from and placed upon the supporting members in a predetermined manner.

15 The carriers, by means of which the work holders are transferred from one bath to another in succession, take the form in the present instance of an endless chain 16 at each side of the baths trained about sprockets 17 disposed in substantially the same vertical plane but below the electro-plating stations, that is, the at-rest positions of the work holders, and over upper sprockets 18 and 19, the former of which are interposed between the sprockets 17 and the latter, at the outer sides of the outermost sprockets. Any suitable means, such as a power belt 21 and pulley may be provided for driving both endless chains in unison. By reason of this arrangement, it will be noted that when the driving pulley is revolved in a counter-clockwise direction viewing Fig. 2, the reaches 22 and 23 of the endless carrier will respectively approach and recede from the several baths. I have, therefore, equipped the endless chains with means for carrying the work holders in such manner that the work will be lowered into the respective baths through the lowering movement of the reaches 22 of the carrier and at the same time the holders will be positioned or set upon the supporting surfaces 15 so as to close the electric circuit of the respective bath. For this purpose the endless carrier chains 16 are each equipped at equally spaced points in lateral alinement with hangers 24 pivotally suspended at 25 and shaped to provide V-shaped supporting surfaces 26. As shown in Fig. 1, referring to the uppermost work holding rod 12, it will be noted that the hangers 24 are arranged to receive the ends of said rod upon the surfaces 26 and to thus carry the work holder in such manner that the latter is freely detachable from the hangers. As a consequence of this construction the work holder may be arrested at a plating station so as to become detached from the hangers. I have, therefore, so relatively arranged the several reaches of the carrier and the supporting members 9 that the surfaces 15 of the latter lie in the path of the above mentioned descending work holding rod 12, the ends of which will be lowered upon said surfaces to

the lowermost point thereof, as the hangers 24 are lowered. The work is now fully immersed in the solution and the circuit closed by the connection between the solution and the electrode 9 through the agency of the work and its holder, so that electrolytic action is set up as long as the work holder 12 remains in contact with the electrode 9. This period of electrolysis is terminated by lifting the work holder from the electrode and the length of the period is determined in the present instance by the speed of the carrier and the distance the hangers 24 travel in the interval between depositing the work holder upon the supporting electrode and lifting the holder therefrom. It will be manifest viewing Fig. 2, that after the work holder is deposited on the supporting electrode 9, the hangers 24 will be lowered with respect to the stationary work holder and thence elevated through the reach or course 23 of the carrier and that during this elevating movement in which the ends of the work holding rod lie in the path of the surfaces 26, said rod will be engaged by said surfaces of the hangers and lifted from the supporting members 9. Thus, a means is provided for mechanically placing the work into and removing it from a bath and for automatically closing the circuit of the bath during only the period that the work is exposed therein.

After the work reaches the first bath it will be elevated in a course substantially directly above the bath so that the solution dripping from the work may fall into the bath. The work will next be lowered into the rinsing bath 4 and detached from the carrier in the same manner and by the same means as it was detached in the instance of the first plating station. However, at the second station, since the bath is simply for rinsing purpose, no electric current is necessary and the act of disconnecting the work holder and connecting it to the carrier has no influence on the circuit. After the rinsing period the work is elevated and thence lowered into the bath 5 for the final electro-plating action, the circuit of the third bath being closed automatically upon exposing the work therein and upon removing it therefrom in the same manner as described with respect to the first bath 3. The work may be removed from the carrier at any time after leaving the final bath, as is obvious.

Referring now to the operation in general, it will be readily understood from the foregoing that I have provided apparatus whereby the work to be plated will be mechanically transferred from one to another of the series of baths at proper intervals requisite for the plating or rinsing or whatever operation is required. And in addition to

simply transferring the work from one bath to another, means has been provided for automatically closing and opening the circuits of the respective baths so that the current will be consumed during only the actual periods of electrolysis. It will be plainly evident that by means of my improvements the work may be subjected to any desired number or series of baths and exposed in the respective baths for any predetermined period, as this period may be governed with accuracy as mentioned above by simply arranging the carrying means for the particular work at hand.

15 It is believed that the foregoing conveys a clear understanding of my improvements, and while I have shown simply for purpose of illustration but one working embodiment, it should be understood that various changes 20 might be made in the construction and arrangement without departing from the spirit and scope of the invention as expressed in the appended claims.

I claim:

25 1. Electro-plating apparatus comprising a series of baths, the electrodes of which are normally out of circuit, a plurality of work holders to each of which is adapted to be attached one or more articles to be plated, 30 means for stationarily supporting a work holder in connection with the negative electrode of a bath, in which position the article carried is immersed in the bath and electrolysis ensues, and continuously operating 35 means for moving intermittently each work holder from the supporting means of one bath to those of another.

2. Electro-plating apparatus comprising a series of baths, the electrodes of which are 40 normally out of circuit, a plurality of work holders to each of which is adapted to be attached one or more articles to be plated, stationary means for supporting a work holder in connection with the negative electrode 45 of a bath, in which position the article carried is immersed in the bath and electrolysis ensues, and an endless carrier adapted to detachably engage with and move the holders successively from the stationary supporting means of one bath to those of another.

3. The combination of a series of baths, an endless carrier mounted so as to travel toward and from each bath in succession, a 55 plurality of work holders detachably connectible with the endless carrier at spaced intervals thereon in such manner that when arrested by being moved toward a bath the work holder will disconnect from the endless carrier and will be subsequently connected to a portion thereof traveling away from said bath, and means for arresting the work holders at a predetermined point in their movement toward the several baths.

4. Electro-plating apparatus comprising a 65 series of baths the electrodes of which are normally out of circuit, an endless carrier mounted so as to travel toward and from each bath in succession, a plurality of work holders so connected with the endless carrier 70 as to be capable of being arrested with respect thereto at a point while approaching the bath, at which point the work is immersed for electrolysis, and, after an interval, to again move with the carrier away 75 from the bath, and means connected with the negative electrode of each bath for arresting a work holder and thereby causing the circuit in the respective bath to be closed until the work holder is subsequently raised 80 by the carrier.

5. In an electro-plating apparatus, the combination of a series of baths, a carrier arranged to travel in proximity to each bath, work holders adapted to be detachably suspended from said carrier, work holder supporting means mounted upon each of said baths whereby the work holders are removed from the carrier and stationarily supported above each bath for a predetermined period, 90 and an electric circuit one terminal of which is connected to said supporting means and the other to electrodes in the respective baths.

6. In an electro-plating apparatus, the combination of a series of baths, work holder 95 supporting means mounted upon each bath, an endless carrier arranged to travel toward and from each bath within the vertical plane of said supporting means, and work holder supporting devices mounted on said carrier 100 and adapted to detachably carry said work holders so that the work holders are automatically deposited upon said supporting means and disconnected from said devices to suspend the work in said baths and are 105 subsequently removed by said devices from said supporting means and conveyed to the next bath.

7. In an electro-plating apparatus, the combination of a series of baths, work holder 110 supporting means mounted thereon, and means for automatically depositing a work holder upon said supporting means where it is stationarily supported for a predetermined period and subsequently removing 115 said holder from said supporting means.

8. In an electro-plating apparatus, the combination of an electrolytic bath, stationary supporting means adjacent thereto, and means for depositing work holders upon said supporting means and removing the same therefrom after predetermined intervals.

9. In an electro-plating apparatus, the combination of a bath, work supporting means connected with one terminal of an 120 electric circuit, an electrode in said bath connected with the other terminal of said circuit, an endless carrier, and means on said

carrier for automatically depositing work upon said supporting means and after a pre-determined interval removing the same therefrom.

5 10. In an electro-plating apparatus, the combination of a bath, a work holder supporting means adjacent thereto, an endless carrier traveling in proximity to said work

holder supporting means, and means on said carrier for automatically depositing a work holder on said supporting means and after a predetermined interval automatically removing the same therefrom and transporting said work holder away from said bath.

HARRY O. SCHUESSLER.
